BILLBOARD CONSTRUCTION

Pierre L. Michael and Kenneth L. Robison,
Houston, Tex.

Application May 12, 1947, Serial No. 747,558

2 Claims. (Cl. 40—125)

1

The invention relates to bill board construction such as those used for advertising purposes and the like.

In the building of present day bill board construction, it has been the practice to put up a frame and inclined bracing with the ends and back usually embodying creosoted poles and various interconnecting wooden structures.

Such a construction is expensive and it is necessary that holes be drilled in the ground at the location of the signboard to receive the frame of the structure. This procedure is time consuming and the operation expensive.

It is, therefore, a primary object of the present invention to provide a signboard construction which is simple in design, sturdy in construction, and which can be built with a minimum of cost and time.

Another object of the invention is to provide a signboard construction which can be built on the desired location without drilling holes in the ground to receive various parts of the structure.

Still another object of the invention is to provide a signboard construction which covers a minimum amount of a plot of ground.

A further object of the invention is to provide in a bill board construction, a pair of vertically positioned beams extending upwardly from the ground, one of which is arranged to support a display panel thereon.

A further object of the invention is to provide in a bill board construction, a pair of vertically positioned beams extending upwardly from the ground, one of which is arranged to support a display panel thereon, said support means being of a construction that permits ready removal of the panel from the beam.

The subject matter of this application relates in part to display panel construction as disclosed and claimed in our issued Patent No. 2,557,387 issued June 19, 1950 and to "Clamp for Sectional Signs" as disclosed and claimed in our issued Patent No. 2,570,365 issued October 9, 1951.

Other and further objects and advantages of the invention will become more readily apparent from a consideration of the following description in connection with the accompanying drawings wherein:

Fig. 1 is a front elevation of the signboard construction showing the preferred general arrangement thereof;

Fig. 2 is an end view of the bill board construction showing the panel support upright and vertical brace beam connected together with the preferred means of laterally supporting the two in the ground;

2

Fig. 3 is a partial section on the line 3—3 of Fig. 1 illustrating the preferred means of supporting the display panel on the bill board construction.

The construction of the bill board 2 is best represented in Fig. 1, and while the bill board may be of any desired configuration, or of any suitable height and length, the construction shown herein is exemplary of the average size signboard used for advertising purposes along thoroughfares such as highways and railroads.

The bill board 2 is shown in Fig. 1 as being positioned on a plot of ground 3. A plurality of spaced vertically arranged panel supports 4 extend downwardly into the ground at 6 and upwardly at 7 back of the panel 8.

Paired with the panel supports 4 and rearwardly thereof are a plurality of uprights or vertically arranged bracing beams 9 extending into the ground at 10 and upwardly to the point 11 about midway of the panel 8. These beams are shown connected to the panel supports 4 by suitable means such as the connecting beams 12 which are shown connected to the panel supports 4 and brace beams 9 by suitable means such as welds 13 and bolts 14 respectively.

The panel 8 may be of any suitable material such as sheet metal or the like, and is shown in Fig. 1 as being composed of planking 15 suitably connected together and trimmed with the moulding 16.

The back of the panel 8 is provided with suitable means such as the formed holder 17 which is provided with a flange 18 for connection to the back of the panel 8. Extending rearwardly thereof is a portion 19 which is bent downwardly at 20 forwardly at 21 and upwardly at 22. Any suitable number of such holders may be provided on the back of the panel 8 for engagement with suitable cofitting means such as shaped bolts 23 connected through the panel support at 24. The bolt 23, extending forwardly at 25, is bent upwardly at 26 in the vertical plane of the bolt 23 and is inclined rearwardly at 28 and bent parallel and rearwardly at 30 and in the same plane as the portion 31.

A nut 33 is provided to engage the threads 34 on the bolt 23 so as to position the panel 8 firmly against the panel support 4. Additional means such as the bolt 40 secured through the moulding 16 and panel support 4 serve to give additional rigidity to the structure.

Such a construction permits ready positioning of the panel 8 upon the supports 4 by simply matching the formed holder 17 on the panel and the shaped bolts 23, and then securing the panel

in position by tightening up on the nut 33 and the bolt and nut 40. It has been found that sliding the panel onto the beams from either end provides a means of easy positioning or removal of the panel from the bill board construction.

Lateral brace beams 43 and 44 are positioned adjacent the ground level 3 and extend downwardly thereinto at 45 and 46. These beams are connected by any suitable means such as the bolts 47 to the panel support and upright brace 9 at 48 and 49 respectively. A cross beam 50 may be connected on the rear side of the panel supports 4 by suitable means such as bolts 51.

Any suitable mechanism such as a hydraulic ram, or steam hammer, may be used to drive the vertical uprights into the ground on the desired location.

A signboard in accordance with the present invention has been found quite satisfactory in use, and has been found to obviate all aforementioned difficulties encountered in present day bill board construction.

Broadly the invention contemplates a bill board construction such as those used for advertising purposes and the like.

The invention claimed is:

1. An outdoor bill board brace and support construction for displaying a panel comprising, a plurality of spaced vertically arranged panel supports extending upwardly from the ground, a vertical bracing beam aligned with and positioned rearwardly of each of said panel supports, said bracing beams extending upwardly to approximately midway of said panel supports, spaced, horizontally disposed connecting beams secured between said vertical supports and bracing beams for holding them together, a pair of brace beams connected to said panel supports and said bracing beams, one of the brace beams of said pair being secured on one side of said panel support above ground level and secured to said vertical bracing beam adjacent and below the ground level and the other brace of said pair being secured to the other side of said panel support above ground level and secured to said vertical bracing beam adjacent and below the ground level with said pair of braces extending downwardly thereinto in opposite directions to cross-brace and anchor said

panel supports and vertical brace beams, a plurality of formed holders extending transversely of the display panel on the back thereof and a plurality of shaped bolts longitudinally spaced along said panel support for engagement with said formed holders to position the panel on the supports.

2. A bill board construction for displaying outdoor advertising panels comprising, a plurality of spaced, vertically arranged panel supports extending upwardly from the ground, a plurality of vertically disposed bracing beams positioned rearwardly of the display panel and in vertical alignment and in close proximity to said panel supports, horizontally disposed, spaced connecting beams secured to said supports and said bracing beams for securing said supports and bracing beams together, a pair of brace beams connected to said panel supports above ground level and secured to said vertical bracing beams adjacent and below the ground level and extending downwardly thereinto to cross-brace and anchor said panel supports and vertical brace beams, and co-fitting means on the panel and on said panel support for securing the panel in position on said panel support, said co-fitting means comprising a rearwardly extending flange on the panel for engagement with a formed bolt extending through said panel support.
